Primary Examiner — Khawaja Anwar*Assistant Examiner* — Mojtaba Tehrani(74) *Attorney, Agent, or Firm* — Park, Vaughan, Fleming & Dowler LLP(57) **CLAIM**

The ornamental design for a fin shaped swimming device, as shown and described.

DESCRIPTION

FIG. 1 is a top perspective view of a fin shaped swimming device, showing our new design;

FIG. 2 is a front view thereof;

FIG. 3 is a back view thereof;

FIG. 4 is a left side view thereof;

FIG. 5 is a right side view thereof;

FIG. 6 is a bottom view thereof; and,

FIG. 7 is a top view thereof.

The broken line in the figure drawings represents unclaimed portion of the design only, which forms no part of the claim thereof.
